UNITED STATES PATENT OFFICE.

JACOB FRANKLIN PIERCY, OF SPOKANE, WASHINGTON.

PUMP FOR PUMPING AND AGITATING CYANID AND ORE SOLUTIONS.

1,376,574.

Specification of Letters Patent.

Patented May 3, 1921.

Application filed May 6, 1919. Serial No. 295,248.

To all whom it may concern:

Be it known that I, JACOB FRANKLIN PIERCY, a citizen of the United States of America, residing at Spokane, in the county 5 of Spokane, State of Washington, have invented new and useful Improvements in Pumps for Pumping and Agitating Cyanid and Ore Solutions, of which the following is a specification.

10 The invention relates to pumps for pumping water, cyanid solutions, and the like.

The principal object of the invention is to provide means for keeping cyanid and pulp solutions constantly agitated while the same 15 is being pumped from a tank or other container, and to bring abundance of air in contact with the solution for the purpose of extracting gold by the cyanid process.

A further object of the invention is to provide 20 a pump of simple construction that can be operated with a minimum of power.

A further object of the invention is to provide valves of special construction adapted for the main purpose of the invention.

25 In the accompanying drawings like characters of reference are provided for similar parts in all the views, and in which, Figure 1, is a vertical cross sectional view of the pump taken on the line *a*, *a*, of Fig. 2;

30 Fig. 2 is a plan view of the pump; Fig. 3 is a detail on an enlarged scale taken on the line *b*, *b*, of Fig. 1; Fig. 4, is a detail view of a section for clamping the canvas or other flexible material to the rim of the 35 bowl of the pump.

The pump consists of a pipe 1, a bowl 2, a seat valve 3, a head valve 4, a plunger 5, canvas or other flexible connections 6, a rim 7, a crank shaft 8 for operating the 40 plunger 5, sections 9 for holding the canvas to the rim of the bowl, and rings 10 that constitute the plunger head and between which the said canvas or other flexible material is clamped. The sections 9 are made so that the side facing the center 45 of the pump is curved more than the rim wherein they are inserted, so as to take up whatever slack there may be in the canvas 6. A number of these sections are provided 50 all along the rim of the bowl 2, and they are held in position by means of wedges 11, which are screwed down by the bolt 12.

The sections 9 and the wedges 11 are further held in position by means of the retaining rim 13, and the overlapping rim 14, 55 which form a part of the bowl 2. The canvas 6 is stretched over the overlapping rim 14, and goes partly around the sections 9. As in practical use the said canvas will wear out frequently, and must be replaced 60 these means are provided to readily remove the canvas and put another in its place. The large bowl 2, the plunger 5 and the canvas 6, serve to keep the cyanid solution in agitation and admit a certain amount 65 of air to the solution, which becomes mixed with the solution. The solution as it is being forced out of the bowl comes on top of the canvas over a wide surface and is thus thoroughly exposed to the air before it enters into the filtering tank. The seat valve 3 has prongs attached to it at the bottom and one at the top, which serve to steady it and keep it in position. The head valve 4 has prongs attached to it at the bottom 70 and two guide pins 15 and 16 to the top, which serve to hold it in position. The rim 7 is detachable and serves to keep the solution from running off the canvas 6, except through the channel 17, which connects with 75 the filtering tank 18.

The crank shaft 8 is attached to a beam 19 by means of bearings 20 and 21. Said beam is attached to the framework that serves to support the battery of tanks. 80

Having thus described my invention what I claim is:

In a pump comprising a pipe, a bowl attached to said pipe, a plunger, a flexible covering connecting said plunger with said bowl, means to attach said covering to said plunger, a sectional inner rim having means for receiving the slack of said flexible covering, and means for attaching and firmly locking said sections of said rim to the rim 90 of said bowl, so as to substantially hold said flexible covering firmly to said bowl. 95

In testimony whereof, I affix my signature in the presence of two witnesses.

JACOB FRANKLIN PIERCY.

Witnesses:

J. E. McANDREW,
JOHN J. HUMMEL.
